UNITED STATES PATENT OFFICE.

WILLIAM K. WILLIAMS, OF GRAND RAPIDS, MICHIGAN, ASSIGNOR TO GRAND RAPIDS SHOW CASE COMPANY, OF GRAND RAPIDS, MICHIGAN, A CORPORATION OF MICHIGAN.

SHOW-CASE.

No. 884,549.

Specification of Letters Patent.

Patented April 14, 1908.

Application filed July 8, 1907. Serial No. 382,618.

To all whom it may concern:

Be it known that I, WILLIAM K. WILLIAMS, a citizen of the United States of America, residing at Grand Rapids, in the county of Kent and State of Michigan, have invented certain new and useful Improvements in Show-Cases; and I do hereby declare the following to be a full, clear, and exact description of the invention, such as will enable others skilled in the art to which it appertains to make and use the same.

My invention relates to improvements in show cases and more particularly to show cases known as "frameless" or "all glass" show cases; and its object is to provide improved means for securing the glass plates in place; and to provide the device with various new and useful features hereinafter more fully described and particularly pointed out in the claims.

My device consists essentially of clips secured to the vertical plates at their upper front corners, a back frame, straps having hooks engaging the clips on the front plate and extending between the upper edge of the end plates and the top plate, and with their rear ends secured to the back frame, and clamps adapted to engage the clips and hooks to secure them to each other, said clamps also being provided with upwardly projecting members to engage and hold the top plate in place, and by which the clamp is held in place, and in various features of combination and arrangement, as will more fully appear by reference to the accompanying drawings, in which:

Figure 1. is a perspective showing a portion of one end of a show case embodying my invention; Fig. 2. an enlarged detail of the front upper corner thereof with the top plate removed; Fig. 3. a vertical section of the same with the top plate added; Fig. 4. a perspective detail of the metal strip extending from front to rear; Figs. 5 and 6 perspective details of a pair of clips; Fig. 7. a perspective detail of the clamp; Fig. 8. a perspective detail of the clip and clamps assembled and viewed from the under side; and, Fig. 9. a perspective detail of the fastenings at the rear corner.

Like numbers refer to like parts in all of the figures.

1 represents the back frame, preferably of wood, with any convenient doors or other means of gaining access to the interior of the

case; 2 represents the end plate of the case; 3 the front plate of the same; and 4 the top plate (these plates preferably of heavy plate glass); 7 and 8 represent metallic clips preferably formed of sheet metal, which respectively embrace the adjacent upper corners of the plates 2 and 3 and are rigidly secured thereto in any preferred manner. These clips are recessed in their lower front edges as at 9 to receive a hook 15 on the end of a strap 5, and lugs 16 on the clamp 10. This strap extends horizontally rearward upon the upper edge of the plate 2 and at its rear end is secured to the frame 1 in any convenient manner, preferably by screws inserted therein. Said strap securely holds the front plate 3 in place against the forward edge of the end plate 2. To further secure the end plates in place the edge of the plate is inserted in a groove in the back 1 and a clip 18 is secured to the rear upper corner of the plate and provided with a projection 20 embedded in the back 1 and secured therein by a screw. To further secure the plates at the front upper corners, a clamp 10 preferably made of sheet metal is so formed as to cover the outer surface of the clips 7 and 8, and the hook 15 of the strap 5. This clamp is provided at each end with inwardly turned edges 11 forming dovetail grooves to receive the vertical edges of the outer members of the clips 7 and 8 and thus hold the same securely connected together with the hook 15. The clip 8 also has lugs 17 struck up to engage the clip 7 and hold the same securely against the clamp.

To secure the top plate 4 in place, I provide upwardly projecting hooks 12 and 13 extending outward and upward to engage the edges of the plate 4, one or both of which hooks being also extended inward above the plate 4 to hold the same down in place, and also to hold the clip 10 from sliding downward, and the clip is held from moving upward by inwardly projecting lugs 16 engaging the recesses 9 in the under edges of the clips 7 and 8. On the end frame I also provide a corner plate 14 having a hook 19 and a projection 21 to engage the plate 4, which plate is slid to place from the rear forward beneath the hooks 13, and the corner plates 14 secured in place by screws, when the structure will be securely locked thereby, and all the plates held in place by these fastening means. To cushion the plate 4 and also to form tight joints, a strip of felt or other

elastic material 6 is preferably placed between the strips 5 and the plate 4.

What I claim is:

1. In a show case, in combination with a back, a front plate, and an end plate; a clip attached to the corner of the front plate, and a strap secured to the back at one end and having a hook on the other end extending over the front of the clip and engaging the lower edge of the same. 10
2. In a show case, in combination with a back, a front plate and an end plate; clips secured to the adjacent corners of the plates, a strap having a hook at one end engaging the clip on the front plate and secured to the back at the other end, and a clamp embracing the clips and hook. 15
3. In a show case, in combination with a back, an end plate, a front plate, and a top plate; clips attached to the adjacent corners of the end and front plate, a strap having a hook at one end engaging the clip on the front plate, said straps extending along the upper edge of the end plate and secured to the back at the other end, a clamp embracing the clips and hook and having inwardly turned ends engaging the ends of the outer members of the clips, and upwardly projecting hooks on the clamp to engage the edge 25 of the top plate. 30
4. In a show case, in combination with a back, an end plate, a front plate and a top plate; clips secured to the respective adjacent corners of the end plate and front plate, a strap having a hook at one end engaging the 35 front and bottom of the clip on the front plate, said strap also extending along the upper edge of the end plate and attached to the back at the other end, a clamp embracing the clips and hook and having inwardly turned ends engaging the ends of the outer members of the clips, upwardly projecting hooks on the clamp to engage the front and end edges of the top plate, one of said hooks also being extended inward above the top 40 plate. 45
5. In a show case, the combination of a back frame having a groove, an end plate inserted in the groove, a clip attached to the end plate and having a projection secured to the frame, a front plate and a top plate, clips attached to the front upper corners of the respective end and front plates, a strip having a hook at one end engaging the clip on the front plate and extending along the upper edge of the end plate and secured to the back at the other end, a clamp embracing the clips on the end and front plate and having inwardly turned ends forming grooves to receive the ends of the outer members of the 50 said clips, lugs on the clamp and engaging the under edges of the clips, and hooks on the clamp, said hooks engaging the edge of the top plate. 55

In testimony whereof I affix my signature 65 in presence of two witnesses.

WILLIAM K. WILLIAMS.
